UNITED STATES PATENT OFFICE

JOHN KEENAN, OF CHICAGO, ILLINOIS

HAIR TRIMMER AND DRESSER

Application filed November 15, 1928, Serial No. 319,672. Renewed July 3, 1930.

This invention relates to improvements in razors of the type set forth in my pending application, Ser. No. 286,534.

The primary object of this invention is to provide a device of the above mentioned character having a plurality of cutting blades which may be employed independently.

Another object of this invention is to provide a device of the above mentioned character which is adapted to include a handle and blades mounted on opposite ends of the handle which may be alternately used in shaving or cutting hair.

A still further object of this invention is to provide a device of the above mentioned character, having a spring clip member for holding the razor blade in operative position and means also being provided for moving the cutting edge of the razor blade into and out of operative cutting position.

Other objects and advantages of this invention will become apparent during the course of the following description forming a part of this specification and in which Figure 1 is a longitudinal plan view of an embodiment of this invention, showing the relative parts for holding the razor blade in cutting position.

Figure 2 is a similar view showing the clamping springs partly in cross section.

Figure 3 is a longitudinal elevational view showing the arrangement of the opposite blade holders carried by the spring clips.

Figure 4 is an end view showing the contour of the blade holding sections.

Figure 5 is a cross sectional view taken on lines 5—5 of Figure 1 showing the arrangement for holding the razor blade in position upon the blade holder.

Figure 6 is a cross sectional view taken on lines 6—6 of Figure 1 showing the manner in which the blade is slidably carried by the blade holder.

Figure 7 is a fragmentary cross sectional view taken on lines 7—7 of Figure 1 showing the relation of the spring holder to the blade carrier and the sliding connection between the blade holder and the comb.

Figure 8 shows a modified form of the invention and is a longitudinal plan view of

the same showing a different form of sliding connection for the blade holder.

Figure 9 is a longitudinal plan view similar to Figure 8 showing the spring holding clips broken away and the slots in the comb portions for slidably carrying the blade holder.

Figure 10 is an elevational view of the modified form of the invention showing the arrangement of the spring clips for holding the blade carrying plates in position.

Figure 11 is an end view of the modified form showing the cross sectional contour of the comb holder.

Figure 12 is a cross sectional view taken on lines 12—12 of Figure 8 showing the pivot pin carried by the spring holding clip for holding the razor blade in position.

Figure 13 is a cross sectional view taken on lines 13—13 of Figure 8 showing the sliding connection between the blade holder and clamping plate for holding the razor blade in place, and

Figure 14 is a longitudinal cross sectional view taken on lines 14—14 of Figure 8 showing the positions of the relative parts of the blade holder and the sliding connections therefor.

For the purpose of illustration attention is first directed to Figures 1 to 7 inclusive wherein is shown a handle 6 having enlarged portions 7 at the opposite ends thereof. Each end portion 7 is triangular in cross section as shown in Figures 5 and 6 and each triangular cross section portion is provided with a series of furcations 8 arranged in such a manner as to provide a series of comb teeth 9.

Each opposite end portion 7 is provided with a pair of slots 10 which extend transversely in respect to the handle 6 and the slots 10 are adapted to receive the flanges 11 formed on the blade clamping plate 12. The blade clamping plate 12 is provided with lugs 13 which are adapted to pass through openings in a well known type of razor blade. The construction described allows free transverse movement of the blade clamping plate 12 and the razor blade 14 which is clamped

between the clamping plate 12 and end member 7.

A spring member 15 is secured to the handle 6 by a screw 16 and its free movable end is provided with a pin 17 which is in alignment with an opening 18 in the clamping plate 12, so that the spring clip 15 may be moved relative to its pivot point 16 thereby causing the blade clamping plate 12 and razor blade 14 to be moved transversely. 10 The clamping spring 15 may be bent or offset to provide easy sliding movement of the clamping plate 12 relative to the enlarged portion 7 of the handle 6.

The comb members 9 may be bent laterally to provide a closer engagement with the razor blade 14 and thereby prevent hairs from becoming wedged between the blade 14 and the combs 9. The longer plane portion opposite the cutting blade 14 is adapted to engage 20 the surface of the skin while being used by a barber or the operator of the razor holding device.

Attention is now directed to Figures 8 to 14 inclusive wherein is shown a modified form of razor blade holder which is similar to the form shown in Figures 1 to 7 inclusive with exception that the modified form shows a different sliding connection between the clamping plate and the holder for the razor blade.

The modified structure includes a handle 6¹ having opposite enlarged portions 7¹ which are formed integral with the handle portion 6¹. Each enlarged portion 7¹ is provided with opposite comb teeth 8¹. The two sets of comb teeth 8¹ are provided in the modified construction for providing four independent cutting surfaces for the interchangeable blades. The blade holder 25 is provided with pins 26 adapted to be received in openings 27 in the enlarged portion 8¹, and the clamping plate 25 is adapted to clamp the razor blade 28 therebetween. The pins 26 formed on the clamping plate 25 are adapted 45 to register with the openings in a well known make of razor blade 28 and the pins 26 are adapted to slide in the arcuately slotted openings 27. A clamping spring 29 is slotted as at 30 and is secured to the handle portion 6¹ 50 by a screw 31 having a bearing surface 32 for the slot 30. The opposite end of the spring clip 29 is provided with a pin 33 which is adapted to pass through the clamping plate 25 and through an opening in the 55 razor blade 28 which aligns with the slotted opening 34. The pin 33 is slidably received in the opening 34 and thereby allows transverse movement of the clamping plate 25 and razor blade 28 relative to the comb portion 8¹.

Either one of the comb portions 8¹ may be used and it will be readily seen that the clamping plate 25 and razor blade 28 may be transversely shifted from one set of comb teeth to the opposite set of comb teeth.

The device described may be employed for cutting hair and the blade may be adjusted relative to the edge of the comb teeth for cutting more or less hair as may be desired.

It is to be understood, that the forms of the invention herein described are to be taken as preferred examples of the same and that various changes in the shape size and arrangement of parts may be resorted to without departing from the spirit of the invention or the scope of the subjoined claims.

Having thus described my invention, what I claim is:

1. A razor blade holder, a handle, comb teeth formed on a razor clamping plate slidably carried by the ends of the handle, said clamping plate adapted to be moved transversely in respect to the handle, a razor blade adapted to be carried by the clamping plate positioned between the clamping plate and the comb teeth portions of the handle, and a spring clip having one of its ends secured to the handle portion and its opposite end secured to the razor blade clamping plate for holding the same in position relative to the comb teeth sections.

2. A razor blade holder, including a handle portion, comb teeth formed on lateral edges of the handle, a clamping plate adapted to be carried adjacent to the comb teeth portions, pins formed on the clamping plate adapted to be received in transverse slots formed on opposite ends of the handle, a razor blade adapted to be carried by the pins on the clamping plate, a spring clip having one of its ends bifurcated for receiving a screw which is secured to the handle portion and a pin formed on the opposite end of the spring clip adapted to pass through an opening in the clamping plate and also through an opening in the razor blade and thence into a transverse intermediate slot formed on the opposite ends of the handle.

In testimony whereof I affix my signature.

JOHN KEENAN.
